UNITED STATES PATENT OFFICE.

THOMAS H. ELLIS, OF ST. LOUIS, MISSOURI, ASSIGNOR OF ONE-FOURTH TO J. U. MEN-
TEER, ONE-FOURTH TO S. R. TYLER, AND ONE-FOURTH TO D. A. RUEBEL, ALL OF
ST. LOUIS, MISSOURI.

VACUUM MASSAGING DEVICE.

1,122,886.

Specification of Letters Patent.

Patented Dec. 29, 1914.

Application filed February 19, 1914. Serial No. 819,625.

To all whom it may concern:

Be it known that I, THOMAS H. ELLIS, a citizen of the United States, residing at the city of St. Louis and State of Missouri, have 5 invented a new and useful Vacuum Massaging Device, of which the following is a specification.

This invention relates to massaging devices of the type in which a partial vacuum 10 and a corresponding suction is created by the pressure of the device against the body.

The device consists of two telescoping members divided into three non-communicating chambers from two of which the air 15 is ejected by the telescoping movement of the members, and the other of which is enlarged so as to reduce the air pressure over the portion of the body covered by the device, thereby creating a strong suction in 20 order to facilitate and improve the circulation of the blood through and to develop the tissues of the massaged portions of the body.

An object of the invention is to provide a conveniently manipulated device for massaging the body, comprising two telescoping members one of which is provided with a concave wall at one end, the periphery of which is adapted to press against the body, the interior of the two members being divided 25 into three non-communicating chambers from two of which the air is ejected by the pressure of the device against the body, and the third chamber being enlarged by the telescoping movement of the two members, 30 and a passage for conducting the air from the space between the concave wall and the body into the enlarging chamber.

With the foregoing and other objects in view my invention consists of the novel construction, combination and arrangement of parts one embodiment of which is illustrated 35 in the accompanying drawings in which,—

Figure 1 is an outer end elevation of the assembled device. Fig. 2 is a longitudinal 5 sectional view. Fig. 3 is an end elevation illustrating the end which is pressed against the body when the device is used. Fig. 4 is a view partially in section illustrating the position of the parts during the massaging action.

As illustrated in the aforesaid drawings the device includes a tubular member 1 having one end closed by a wall 2 which is depressed inwardly so as to provide an external concave recess or depression at the

end of the tubular member 1. A small tube 3 is rigidly attached to the inner side of the end closure 2, and has communication with the dished recess or depression outside of the end closure 2 through a hole 4 opening into 60 said tube. The other tubular member 5 telescopes within the member 2, and is provided with a partition 6 having a central opening through which the tube 3 extends. The partition 6 divides the interior of the 65 telescoped members into non-communicating chambers, so that the air within the chamber below said partition cannot pass above said partition. A spring 7 of the expansion type encircling the tube 3, has one end seated 70 upon the end wall 2, and the opposite end pressing against the partition 6 effectively to actuate the tubular members to their expanded adjustment, as illustrated in Fig. 2.

The space above the partition 6 is divided 75 into two non-communicating chambers by a piston attached to the end of the tube 3. The piston includes a number of disks 8, preferably of elastic and flexible material, clamped between two metallic disks or plates 80 9. The piston thus constituted is detachably secured to the end of the tube 3 by a screw 10 passing through all of the members of the piston and engaging in the threaded upper end of said tube.

It will be observed that in the idle or expanded position of the parts the interior of 85 the tubular members is divided into three non-communicating chambers A, B, and C. When the tubular member 5 is pressed inwardly in opposition to the power of the spring 7 the air is ejected from the chamber A through the openings 11, and the air is ejected from the chamber C through the opening 12. The chamber B has communication with the exterior through an opening 13 into the tube 3, and thence through the opening 4. It is obvious that when the parts are pressed together to the position illustrated in Fig. 4 the chambers A and C 90 95 are reduced, and the chamber B becomes enlarged as the partition 6 is moved away from the piston attached to the end of the tube 3. If the end of the tube 1 be pressed against the body so that the air cannot pass 100 from the exterior into the space between the wall 2 and the body, the pressure of the air in said space will be greatly reduced as the chamber B becomes enlarged, thereby effecting a cupping or suction action facilitat- 110

2
ing the circulation of the blood to the parts to which the cupping action is applied. The device thus engaged by suction with the body may be moved from one position to another without becoming disengaged, and obviously such action may be utilized with beneficial results in improving the circulation.

As an aid in securing an engagement which will exclude the air, an elastic rubber ring 14 may be employed and engaged over the rim formed by the connection between the tube 1 and the end wall 2. It is preferable that the rubber ring be detachable, so that it may be removed when not needed, or replaced with another when required. I also prefer to employ a rim or flange 15 attached to the tube 1 to afford a hold for the fingers when the tube 5 is pressed into the tube 1 by the palm of the hand.

It is apparent that there may be many modifications in the construction and arrangement of the parts without departure from the spirit and scope of the invention, and it will be understood that I do not restrict myself to specific features of structure or arrangement.

What I claim and desire to secure by Letters Patent is:

30 1. A device of the character described, comprising two telescoping members forming a tube divided into non-communicating chambers, an open chamber formed at one end of one of said members, a passage placing said open chamber in communication with the remote one of said non-communicating chambers, and means actuating said telescoping members apart, and adapted to yield to manual pressure whereby one of 40 said members may be moved within the other for creating a suction in said open chamber.

2. A device of the character described, comprising a tubular member having a concave chamber at one end, a second tubular member fitting within said first-named tubular member and adapted to be moved longitudinally thereof, said second member being open at both ends, a partition in said 50 second tubular member, a tube constituting a passage leading from said concave chamber to the interior of said tubular members beyond said partition, and a piston carried

by said tube and arranged to divide said second-named tubular member into a sealed 55 and open chamber.

3. A massaging device of the suction type, comprising a tubular suction member adapted to be pressed against the body, a movable tubular member fitting within said suction member, and means for creating a suction upon the body by said suction member by a movement of said second named member toward the body, substantially as specified.

4. A massaging device of the suction type, comprising a tubular suction member adapted to be pressed against the body, a flange carried by said suction member, a movable tubular member arranged to telescope with 70 said suction member, and means for creating a suction upon the body by said suction member when said second named tubular member is moved toward the body, substantially as specified.

5. A device of the character described, comprising a tubular member, a concave wall at one end of said member forming an external chamber, a tubular member operatively mounted in said first-named tubular member, a partition in said second named member, a tube communicating with said external chamber and extending through said partition, a spring interposed between said end wall and said partition, and a piston 85 attached to said tube and forming a chamber in said second named member one end of which chamber is closed by said partition, said chamber communicating with said tube, substantially as described.

6. A device of the character described comprising a tubular member, a second tubular member movably mounted therein, a spring actuating said tubular members apart, partitions dividing said tubular members into non-communicating chambers, and a tube forming a passage between one of said chambers and the exterior, substantially as described.

In witness whereof, I have signed this 1 specification in the presence of two subscribing witnesses.

THOMAS H. ELLIS.
